DRIER AND OFFSET ELIMINATOR

Henry C. Haeckel, St. Louis, Mo.

Application January 24, 1934, Serial No. 708,029

1 Claim. (Cl. 34—12)

This invention relates generally to driers and more particularly to driers for use in combination with printing presses.

In the operation of printing presses, the printed

10 sheets, upon being printed, are generally stacked upon each other. The result is that even with the use of quick drying inks the print does not dry quick enough so that the backs or reverse sides of the sheets receive offsets or are smudged by the ink of the preceding sheet. This impairs the appearances of the sheets and is especially objectionable in case of circulars which are folded for mailing purposes. The use of quick drying ink or the case of "dope" in the ink to facilitate 15 the drying does not entirely obviate these objectionable features but does increase considerably the cost of printing.

One of the objects of the invention is to provide a device arranged adjacent to the printing 20 press and comprising a plurality of horizontally disposed pans movable in a vertical or horizontal plane at a predetermined speed with respect to the press whereby each printed sheet is placed on a pan and dries during the cycle of movement 25 of said pan and is discharged from said pan at suitable periods of the cycle of movement of the pan.

Another object of the invention is to provide 30 a drier comprising a pair of spaced-apart endless chains and a plurality of horizontally disposed pans pivotally mounted on said chains in spaced-apart relationship whereby the matter to be dried is placed on said pans and is allowed to dry during the cycle of movement of each pan 35 there being means provided for tilting each pan at the appropriate time during the cycle of movement thereof to discharge the dried material into a suitable container.

Further objects of the invention are to provide 40 a drier of the class described and drying means arranged adjacent to the upper end thereof for acting upon said material and facilitating the drying thereof.

Still other objects of the invention are to provide 45 an offset eliminator arranged adjacent to one side of a printing press and comprising a vertically disposed support, means journaled in the lower and upper ends thereof, respectively, for carrying a pair of spaced-apart sprocket 50 chains, a plurality of horizontally disposed pans arranged in spaced-apart relationship, and each pivotally mounted at its sides to the links of the respective chains, means for driving said chains by the driving mechanism of said press and in 55 a predetermined speed relationship therewith,

and means for engaging each pan just before the completion of its travel and tilting it to cause the material carried thereby to be discharged therefrom.

With these and other objects in view, my invention consists in certain novel features of construction and arrangement of parts, hereinafter more fully described and claimed, and illustrated in the accompanying drawing, in which—

Figure 1 is a side elevational view of the drier. 10

Figure 2 is an enlarged front elevational view of the lower end thereof.

Figure 3 is an enlarged horizontal cross section taken on line 3—3 of Figure 1.

Figure 4 is an enlarged detail view showing the 15 means for tilting the pan.

Figure 5 is an enlarged cross sectional detail view showing means for pivotally suspending the pan on the links of the chains.

Figure 6 is an enlarged detail cross section 20 taken on line 6—6 of Figure 3.

Figure 7 is an enlarged cross section showing structural details of the support.

Figure 8 is an enlarged detail cross section of the driving connection. 25

Referring by numerals to the accompanying drawing, 10 indicates a vertically disposed support comprising a pair of side frames 11 connected together at a number of points by horizontally disposed transverse members 12. Each 30 side frame preferably consists of a pair of vertically disposed channel members 14, a base 15, a top 16, and intermediate cross pieces 17. The latter are preferably channel-shaped in cross section and are secured to vertical members 14 35 by angles 18. Each pair of cross pieces 17 of the side frames 11 is connected together by one of the transverse members 12.

The base 15 preferably consists of channel-shaped pieces and extends a suitable distance to 40 each side of channel member 14. A gusset plate 19 is preferably secured to the outer flanges of the lower end of each vertical member 14 and the corresponding end of base 15.

A pair of axially aligned bearings 20 is secured 45 to the lowermost cross pieces 17 and a horizontally and transversely disposed shaft 21 is journaled in said bearings. Similarly a pair of bearings 22 are secured to the uppermost cross pieces 17 and carry a shaft 24. These shafts are pref- 50 erably disposed centrally of support 10 in the same vertical plane with each other. A pair of comparatively large sprocket wheels 25 is fixed to the lower shaft 21 and a pair of similar sprocket wheels 26 is secured to the upper shaft 24. 55

These sprocket wheels are arranged each near one end of the corresponding shaft and in a vertical plane with the corresponding wheel of the other shaft. Operating over each pair of vertically aligned wheels 25 and 26 is a sprocket chain 27. Certain links of chains 27 are provided with oppositely and horizontally disposed pins or studs 28, each opposed pair of which is arranged coaxially with each other. Pivotally suspended 10 from each aligned pair of pins 28 by means of bearings 29 is a pan 30. This pan is balanced so that it occupies normally horizontal position.

The material to be dried, in this case, the freshly printed sheet, is laid on each pan as it 15 passes a given point. Each pan is preferably provided at its sides with upwardly projecting flanges 31 and at its rear or inner end with a similar flange 32. The forward or outer end is open but may be provided on its underside with 20 a downwardly projecting flange 34 for reinforcing purposes.

Shafts 21 and 24 are so actuated that the portions of chains 27 located adjacent to the printing press are moved upwardly while the other 25 portion travels downwardly. In this manner, the pans receiving the printed sheets move upwardly, then over the upper shaft 24, and under an electric heater 35 conveniently located above said pans, and then downwardly on the other side of 30 the support and under the lower shaft 21. Just before the completion of the cycle of movement of the pan, the latter is tilted on its pivots 28 to cause the material carried thereby to be discharged into a suitable container in an open top 35 box 36 arranged below the forward edge of said tilted pan.

Where the drier is used to dry printed sheets, this container is preferably in the form of the usual jogger box which is operated to align the 40 stacked sheets with each other.

The tilting means consists of a roller 37 revolvably disposed in the path of the upwardly traveling pans in such a manner that the edge of one of the upwardly presented side flanges 31 is engaged near its forward end by said roller, thereby causing said pan to tilt on its pivots 28. When the forward end 31a of the flange 31 is carried past said roller, said pan resumes its normal horizontal position. This roller is revolvably mounted 50 on one end of an arm 38 while the other end thereof is attached to one of the side frames. This arm is disposed horizontally and preferably is pivotally mounted in a bracket 39 for movement in a horizontal plane so that it can be moved 55 to displace roller 37 and move the latter from its operative position so as not to affect the pans.

A horizontally disposed member 40 is attached to side members 14 and its outer end is forked so as to receive arm 38, while the latter is moved to 60 bring the roller 37 in operative position. The ends of this forked portion are adapted to receive a removable pin 41 which, when inserted in said apertures, closes said forked end and locks arm 38 against displacement.

When the drier is used in conjunction with a printing press, a suitable driving connection is provided between a shaft 42 carrying the fly wheel 43 of the press and one of the shafts of the driers. Preferably the upper shaft 24 of the drier 70 has one end extended outwardly from the bearing and fixed on said end is a worm gear (not shown). Meshing with this gear is a worm 45 fastened to a horizontal shaft 46 and disposed at right angle to shaft 24. This shaft 46 is jour-

naled in suitable bearings carried by the corresponding side frame 11.

One end of shaft 46 has secured thereto a sprocket wheel 47 over which operates the upper end of an endless sprocket chain 48. The lower end of this chain engages a sprocket wheel 49 which is loosely arranged on the projecting end of the fly wheel shaft 42. A manually operable clutching means 50 is also arranged on shaft 42 and serves to connect and disconnect the sprocket wheel 49 to and from said shaft, thereby permitting the operation of the press without actuating the drier.

The spacing of the pans 30 and the speed at which they move is so arranged that the sheets 15 dry before they are discharged from the drier and an empty pan moves in receiving position with each printing operation of the press. As the driving means of the drier is coupled with the actuating mechanism of the press it is obvious 20 that when the speed of the press is increased or reduced, the speed of the drier is effected accordingly. The electric circuit of the electric heater or drying means 35 is provided with a usual switch (not shown) so that the heater can be 25 turned on and off at will.

As shown in the drawing, the drier is located in close proximity to a platen press and the pans during their ascending movement pass close to the fly wheel thereof. A bumper or shock absorber 51 receives the impact of each pan after it is released from its tilting position, thereby preventing the pan from striking against the fly wheel. This bumper consists of a strip of leather 52 of suitable width and disposed vertically in front of the pan adjacent to the point of its release from roller 37. Normally this leather piece is spaced from the path of travel of said pans but is engaged by the pan when the latter is set in swinging motion, upon its release 40 from roller 37. This bumper not only eliminates the striking of the pan against the fly wheel and the consequent noise produced thereby, but also steadies the pan and prevents swinging motion thereof.

The strip of leather is supported by the front inwardly bent end 53 of a strip 54 which latter is secured to the corresponding side frame 11 and projects forwardly therefrom.

An idler 55 is mounted by a bolt 56 in member 50 14 adjacent to each sprocket wheel 25 and 26 so that the chain 27 intermediate said wheels are disposed closer to each other than the diameters of said wheels, thereby bringing pans 17 also closer together.

Preferably the drying pans are disposed in two vertical tiers, thereby providing a large capacity with a minimum amount of floor space. The drier is so constructed that it can be applied to platen printing presses already installed without requiring rearrangement of the latter or mechanical changes in the driving mechanism of the press. The spacing and the size or the widths of the pans can be varied to suit the requirements of the particular case.

My improved drier can be used in connection with high speed or other cylinder presses equally as well as with platen printing presses. In such a case it would be preferable to arrange the drier so that the pans would travel in a horizontal 70 plane and could be used to carry the printed sheets to a folding machine or any other machine or could be discharged into a regular paper jogger. As such an arrangement would eliminate the necessity of slip sheeting, a great saving in 75

time and labor could be effected. The slip sheeting consists in placing a sheet of clear paper on top of a printed sheet so as to separate it from the next sheet and prevent the ink of the underlying printed sheet from adhering to the back of the following sheet. It is especially necessary in high class work, or where a highly finished paper is used. However, it calls for an extra man to slip the sheets as the printed sheets are discharged and it slows down the work of the press.

Furthermore, the slipped sheets have to be removed, thereby requiring additional time and labor. By the use of my drier the expensive slip sheeting is eliminated and the press can be operated at its maximum capacity.

I claim:

A device of the class described comprising in combination a framework support, a plurality of horizontally disposed shafts journaled therein in spaced-apart relation, a pair of sprocket wheels

fixed on each shaft, each near each end of said shaft, a pair of endless sprocket chains operating over the corresponding sprocket wheels, a plurality of pans, means for pivotally suspending each pan in a horizontal position from said chains, an arm movably mounted on one side of said framework support near the lower end thereof, a roller journaled on the outer end of said arm, said arm being movable to bring said roller into the path of movement of said pans, whereby the forward end of one side of each pan is engaged by said roller and said pan is tilted forwardly on the commencement of its forward movement, said arm being movable to bring said roller out of the path of said pans, a downwardly presented electric heater arranged in the upper end of said framework support for drying the material contained in each pan as the latter traverses said upper end, and driving means engaging one of said shafts.
